US0D1034245S

(12) **United States Design Patent** (10) **Patent No.:** **US D1,034,245 S**
(45) **Date of Patent:** **** Jul. 9, 2024**

(54) **WEARABLE DEVICE**

(71) Applicant: **Google LLC**, Mountain View, CA (US)

(72) Inventors: **Junyong Park**, San Francisco, CA (US); **Benjamin Patrick Robert Jean Riot**, Alamo, CA (US); **Irina Igorevna Kozlovskaya**, San Francisco, CA (US); **Eric John Fairbanks**, Lafayette, CA (US); **Brian Dennis Paschke**, San Francisco, CA (US); **Cédric Eric Jean-Edouard Bernard**, San Francisco, CA (US); **Jonah Avram Becker**, San Francisco, CA (US); **Gregoire Ludovic Vincent Vandenbussche**, San Francisco, CA (US)

(73) Assignee: **Google LLC**, Mountain View, CA (US)

(**) Term: **15 Years**

(21) Appl. No.: **29/856,520**

(22) Filed: **Oct. 14, 2022**

Related U.S. Application Data

(63) Continuation of application No. 29/828,096, filed on Feb. 24, 2022, now Pat. No. Des. 973,517, which is

CLAIM

The ornamental design for a wearable device, as shown and described.

DESCRIPTION

FIG. 1 is a top perspective view of a wearable device showing our new design;

FIG. 2 is a bottom perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.

The grayscale shading depicts a contrast which is part of the claimed design without claiming any particular color. The broken lines in the figures depict portions of the wearable device that form no part of the claimed design.

1 Claim, 4 Drawing Sheets

Related U.S. Application Data

a continuation of application No. 29/797,847, filed on Jul. 2, 2021, now Pat. No. Des. 985,554.
